UNITED STATES PATENT OFFICE.

HUGH W. SANFORD, OF KNOXVILLE, TENNESSEE.

RAILWAY CAR.

Original application filed August 31, 1923, Serial No. 660,416, now Patent No. 1,486,547, dated March 11, 1924. Divided and this application filed March 10, 1924. Serial No. 698,222.

To all whom it may concern:

Be it known that I, HUGH W. SANFORD, a citizen of the United States, residing at Knoxville, in the county of Knox and State 5 of Tennessee, have invented a new and useful Improvement in Railway Cars, of which the following is a specification, reference being had to the accompanying drawing.

My invention relates particularly to mine 10 cars and other cars of any type wherein the frame of the car has side sills and end sills connecting the side sills.

This application is a division of my application, Serial Number 660,416, filed 15 August 31, 1923, now Patent 1,486,547, granted March 11, 1924, for Letters Patent of the United States for an improvement in railway cars.

That application illustrates and describes 20 an end sill formed chiefly of a rolled steel plate bent into desired form and adapted to be joined to the ends of the side sills to form a rectangular frame for the car body. In that application the end sill is shown 25 in two forms, the first being adapted to receive an ordinary coupling link for coupling the meeting ends of two such cars to each other while the other form includes a filling member in which is a socket adapted to receive a spring-controlled draw bar. This second form is made the subject matter 30 of this application, this application thus becoming a division of my said application, Serial Number 660,416.

In the accompanying drawings,

Fig. 1 is a plan of a structure embodying my improvement;

Fig. 2 is an elevation looking at the structure of Fig. 1 from the left;

Fig. 3 is a front elevation of the structure shown by Figs. 1 and 2, the view being parallel to the length of the car;

Fig. 4 is a plan showing a sheet steel blank from which is made the body of the end sill;

Fig. 5 is a perspective of said end sill detached from other parts;

Fig. 6 is a perspective of one of the corner members used for joining the side sills to the end sill;

Fig. 7 is an upright section on the line 7—7, of Fig. 1, looking in the direction of the arrow;

Fig. 8 is a horizontal section on the line 8—8, of Fig. 3;

Fig. 9 is an upright section on the line, 9—9, of Fig. 1, looking in the direction of the arrow;

Fig. 10 is an upright section on the line, 10—10, of Fig. 1, looking toward the right.

Referring to said drawings, A, A are the side sills. In the form shown in the drawings, these sills are of channel-form with flanges, A¹, directed outward.

B is the steel plate member of the end 65 sill. This is of channel form and has an upright web, B¹, (presenting a flat back face) and an upper horizontal flange, B², and a lower horizontal flange, B³. The corners of the flange, B², are cut to make 70 slanting edges, B⁴; and the corners of the lower flanges, B³, are similarly cut to make slanting edges, B⁵ (Figs. 1, 4 and 5). This member, B, is formed by folding the blank of Fig. 4, along the dotted lines, B⁶. The 75 blank of Fig. 4 is cut from a plate of rolled steel of desired thickness. This member, B, is also provided with holes as will be described further on.

In the form shown in the drawings, the 80 plate member, B, is long enough to partially over-lap the adjacent ends of the side sills. Said member and the side sills are joined to each other by means of corner angle members, C. One of these angle 85 members is shown in perspective in Fig. 6. One arm or blade of the angle member rests against the outer flat face of the plate member, B, and is secured to the plate member by bolts or rivets, C¹, extending through 90

said blade and the plate member, B. The drawings show six such bolts or rivets. The other arm or blade of the angle member extends into the space between the flanges, A¹, of the adjacent side sill and bears 95 against the upright web of the side sill. Bolts or rivets, A², extend through said blade and said web to join said parts to each other. In the form shown in the drawings, six such bolts or rivets, A², are used. 100 These corner angle members and the bolts or rivets used for securing these angle members to the plate member, B, and the side sills, A, are to be sufficiently strong to give rigidity to the frame. The web, B¹, of the plate member, B, is wider than the height

of the side sills, A, A, to make space for the filling member.

This filling member, D, is of a length approximately equaling the length of the steel plate member, B, and of a height to fill the space between the flanges, B² and B³, of the plate, B. On the middle longitudinal line of the car, the member, D, has in its upper face a longitudinal channel, D¹, of suitable 10 form to constitute a socket or chamber adapted to receive a spring-controlled draw bar, not shown. In the bottom of the channel, D¹, are an outer opening, D², and an inner opening, D³, which may receive members associated with the draw bar. Bolts, D⁴, extend through the flanges, B² and B³, and through the member, D, and bind said members firmly to each other. In this case, the draw bar and the member, D, project outward 20 beyond the flanges, B² and B³, and take impact from another car.

Opposite each angle member, C, the rear face of the filling member, D, is provided with a recess, D⁵, which makes room for the 25 heads of the adjacent bolts or rivets, C¹.

The filling member, D, may be formed of metal or of wood.

By placing the steel plate member, B, against the faces of the angle members, A, 30 the height of the bumper may be fixed to suit the height of bumpers on other cars with which the new car is to be used. In applying the plate member, B, to the new car, the member, B, being wider than the 35 angle members, A, may be set at the desired height for riveting to the angle members.

I claim as my invention,

1. In a railway-car, the combination with 40 side sills and corner pieces, of a plate metal end sill member formed to present a continuous and upright back face to the corner members and to present upper and lower horizontal flanges free from each other and extending from end to end of the sill, and a filling member located between said flanges and having the socket or chamber adapted to receive a draw bar, substantially as described.

2. A composite end sill for railway-cars, 50 said sill comprising a plate metal channel member formed to present an upright back face and to present upper and lower horizontal flanges directed away from the car frame, and a filling member between said flanges and having a chamber or socket 55 adapted to receive a draw bar, substantially as described.

3. A composite end sill for railway-cars, 60 said sill comprising a plate metal channel member formed to present an upright back face and to present upper and lower horizontal flanges directed away from the car frame, and a filling member located between said flanges and having a socket adapted to 65 receive a draw bar located between and

reaching outward beyond said flanges, substantially as described.

4. A composite end sill for railway-cars, 70 said sill comprising a plate metal channel member formed to present an upright back face and to present upper and lower horizontal flanges directed away from the car frame, and a filling member located between said flanges and having in its upper face a channel covered by the upper of said flanges 75 whereby there is formed a chamber or socket adapted to receive a draw bar, substantially as described.

5. A composite end sill for railway-cars, 80 said sill comprising a plate metal channel member formed to present an upright back face and to present upper and lower horizontal flanges directed away from the car frame, and a filling member located between said flanges and reaching outward beyond said 85 flanges and having in its upper face a channel covered by the upper of said flanges, whereby there is formed a chamber or socket adapted to receive a draw bar, substantially as described. 90

6. A composite end sill for railway-cars, 95 said sill comprising a plate metal channel member formed to present an upright back face and to present upper and lower horizontal flanges directed away from the car frame, and a filling member located between said flanges and having horizontal space adapted to receive a draw bar and having an opening extending outward from said 100 spaces and adapted to receive a member associated with the draw bar, substantially as described.

7. A composite end sill for railway-cars, 105 said sill comprising a plate metal channel member formed to present an upright back face and to present upper and lower horizontal flanges directed away from the car frame, a filling member located between said flanges and having a chamber adapted to receive a draw bar, and upright bolts extending through said flanges and said filling member, substantially as described. 110

8. A composite end sill for railway-cars, 115 said sill comprising a plate metal channel member formed to present an upright back face and to present upper and lower horizontal flanges directed away from the car frame, a filling member located between said flanges and reaching outward beyond said flanges and having a chamber adapted to receive a 120 draw bar, and upright bolts extending through said flanges and said filling member, substantially as described.

9. In a railway-car, the combination of an 125 end sill comprising a plate channel member formed to present a continuous and upright back face and to present upper and lower horizontal flanges free from each other and extending from end to end of the sill and directed away from the car frame, a filling 130

member placed between said flanges and flanges extending from end to end of the chambered to adapt it to receive a draw bar, and a frame member over-lapping and secured to the end sill at each end of the latter, substantially as described. 5

10. In a railway-car, the combination with side sills and corner pieces, of a plate metal end sill member formed to present a continuous upright back face to the corner members the upright dimension of which is higher than the upright dimension of the corner members, and to present upper and lower horizontal flanges extending from end to end of the sill, and a filling member placed between said flanges and being chambered to adapt it to receive a draw bar, substantially as described. 15

11. In a railway car, the combination with side sills and corner pieces, of a plate metal end sill member formed to present an upright back face to the corner members and to present upper and lower horizontal

sill and directed away from the car frame, bolts or rivets extending through the corner members and the upright part of the end sill member, and a filling member recessed to receive the heads of said bolts or rivets and chambered to adapt it to receive a draw bar, substantially as described. 25

12. In a railway-car, the combination with side sills, of a plate metal end sill member formed to present a continuous and upright back face and to present upper and lower horizontal flanges free from each other and extending from end to end of the sill, and a filling member located between said flanges and having a socket or chamber adapted to receive a draw bar, substantially as described. 30

In testimony whereof I have signed my name, this 6th day of March, in the year one thousand nine hundred and twenty-four.

HUGH W. SANFORD.
